United States Patent Office

Des. 188,926
Patented Sept. 27, 1960

188,926

PORTABLE SPACE HEATER

William M. Cooper, St. Louis, Mo., assignor to Champion Heater Co., Inc., St. Louis, Mo., a corporation of Missouri

Filed Mar. 4, 1959, Ser. No. 54,829

Term of patent 14 years

(Cl. D81—20)

FIG. 1.

FIG. 2.

FIG. 3.

FIG. 4.

Fig. 1 is a top plan view of a portable space heater showing my new design;

Fig. 2 is a side elevational view thereof;

Fig. 3 is a front elevational view thereof, and

Fig. 4 is a rear elevational view thereof.

The essential features of the design reside in the portions shown in full lines.

I claim:

The ornamental design for a portable space heater, substantially as shown and described.
